(57) **CLAIM**

The ornamental design for a handle, as shown and described.

DESCRIPTION

FIG. 1 is a top front perspective view of a handle showing our new design;

FIG. 2 is a top plan view thereof;

FIG. 3 is a right side elevational view thereof; the left side elevational view being a mirror image;

FIG. 4 is a bottom plan view thereof;

FIG. 5 is a rear elevational view thereof; and,

FIG. 6 is a front elevational view thereof.

The broken lines shown in FIGS. 1-5 are for illustrative purposes only and form no part of the claimed design.
